[57] CLAIM

The ornamental design for a combined video monitor and camera station, substantially, as shown and described.

DESCRIPTION

FIG. 1 is a top, front and left side perspective view of a combined video monitor and camera station showing our new design;

FIG. 2 is a front elevation view thereof;

FIG. 3 is a rear elevation view thereof;

FIG. 4 is a right side elevation view thereof, the left side elevation view being a mirror image;

FIG. 5 is a bottom plan view thereof; and,

FIG. 6 is a top plan view thereof.
